CLAIM

The ornamental design for a drone detection device, as shown and described.

DESCRIPTION

FIG. 1 is a top perspective view of a drone detection device showing my new design,

FIG. 2 is a bottom perspective view thereof,

FIG. 3 is a front elevational view thereof,

FIG. 4 is a top plan view thereof,

FIG. 5 is a bottom plan view thereof; and,

FIG. 6 is a sectioned end face view taken along line A-A with internal mechanism being omitted thereof.
